UNITED STATES PATENT OFFICE.

CHARLES E. BALL, OF TURLOCK, AND SAMUEL H. BALL, OF LIVINGSTON, CALIFORNIA,
ASSIGNORS OF ONE-THIRD TO SAID SAMUEL H. BALL AND TWO-THIRDS TO SAID
CHARLES E. BALL.

SCRAPER.

Application filed December 19, 1922. Serial No. 607,811.

To all whom it may concern:

Be it known that we, CHARLES E. BALL and SAMUEL H. BALL, both citizens of the United States, and residents of Turlock, in 5 the county of Stanislaus, and Livingston, in the county of Merced, State of California, have invented certain new and useful Improvements in Scrapers, of which the following is a specification.

10 Our invention relates primarily to a scraper such as is used for road construction, land leveling, etc., although it is not limited to any particular work or class of work but is equally adaptable for any use 15 which requires the moving of earth or soils, particularly where it is desired or necessary to move the same for any considerable distance.

Heretofore, in the hauling of earth for 20 any distance, such as in road construction and the like, it has first been necessary to shovel the same into dump or other wagons, haul the same to the desired place of deposit, then dump the same and then use 25 shovels to spread the same.

It is the object of our invention to provide a scraper or scrapers mounted on a frame supported at a suitable distance by 30 wheels and carrying mechanism whereby the scrapers (one or more) may be lowered and loaded in the usual manner and then elevated and transported to the desired place of deposit, a suitable gate being provided to prevent the accidental spillage of 35 the load, and then dumped by tipping in the usual manner, suitable mechanism being provided to control the angle to which the bowl is tipped, whereby the load may be deposited in one place or may be spread to 40 a level as desired.

Other objects and advantages will appear hereinafter and, while we have shown and will describe the preferred form of our invention, we wish it specifically understood 45 that we do not limit ourselves to such preferred form but that various changes and adaptations may be made therein without departing from the spirit of our invention.

In the drawings accompanying and forming 50 a part hereof:

Fig. 1 is a side elevation of our device.

Fig. 2 is a top plan of Fig. 1.

Fig. 3 is an enlarged section on the line 3-3 of Fig. 2.

55 Fig. 4 is a side elevation of our bowl and

its complement parts showing the same in its extreme dumping position.

Fig. 5 is an enlarged detail view of the bowl raising and lowering mechanism.

Fig. 6 is an enlarged detail of our braking mechanism, in its operative position.

Fig. 7 is a view similar to Fig. 6, showing our braking mechanism in its inoperative or released position.

Fig. 8 is a perspective view of our clutch 65 and brake operating lever.

Referring to the drawings our device comprises a substantially rectangular frame 10 supported at its front end upon a pivotal axle 11, which axle is supported at each end 70 by wheels 12. Extending transversely of frame 10, at a distance from its rear end, is an axle 13, supported near each end by bearings 14 secured to the upper face of frame 10, and revolvably mounted upon each 75 end of axle 13 are the rear wheels 15. Wheels 15 are provided with suitable differential devices 16 of any of the well known constructions suitable for this purpose.

Extending upwardly from each side of frame 10 are members 17 and 18 provided with oppositely positioned bearings 19 and 20 and revolvably mounted in these bearings are the bowl elevating shafts 21 and 22. 85 Rigidly mounted upon one of the ends of shafts 21 and 22 are bevel gears 23 and 24, which are in mesh with pinion gears 25 and 26 loosely mounted upon an operating shaft 27. Shaft 27 is revolvably mounted in bearings 28 extending outwardly from member 17. Extending transversely between members 17 and 18, revolute therein, is a driving shaft 29 upon one end of which is rigidly mounted a bevel gear 30 which gear 95 meshes with a pinion gear 31 rigidly mounted upon shaft 27. Rigidly mounted upon shaft 29, near the inner side of member 17, is a sprocket wheel 32 which wheel is connected by a chain 33 to a sprocket wheel 34 100 rigidly mounted upon axle 13, whereby when said axle 13 is rotated shafts 27 and 29 are also rotated. Slidably but relatively non-revolvably mounted upon shaft 29, between the opposed faces of pinion gears 25 105 and 26, is a clutch member 35 the ends of which are provided with clutch jaws 36 and 37 which jaws are adapted to be brought into engagement with the clutch jaws 38 and 39 of pinion gears 25 and 26 respec-

110

tively to cause shafts 21 and 22 to rotate in reverse directions. Rigidly mounted upon the other ends of shafts 21 and 22 are brake drums 40, and surrounding said drums 40 are brake bands 41. As best shown in Figs. 6 and 7, one end of bands 41 are rigidly connected to a bracket 42 extending outwardly from member 18 and the other end lies beneath the end of a flexible member 43 10 also extending outwardly from the outer side of member 18. Extending between the free ends of brake bands 41 is a coil spring 44 which acts to separate said ends when pressure is released from member 43. Extending upwardly from member 18 is an angular bracket 45 in which is slidably mounted a push rod 46 the lower end of which is loosely mounted in an aperture intermediate the free ends of member 43. 15 The lower end of rod 46 is threaded and is provided with a nut 48 by means of which the movement of bands 41 is adjusted. A stud 49 connects the ends of bands 41 and bracket 42 and then extends upwardly and 20 its free end passes through apertures in the ends of members 43 and the other end of bands 41. Pivotally connected to the upper ends of rods 46 is one end of a link 50 the other end of which is pivotally connected to 25 the upper end of a lever 51. Lever 51 has its lower end rigidly connected to a shaft 52 pivotally mounted at its ends in members 17 and 18. The other end of shaft 52 is provided with an upstanding lever 54 on 30 the upper end of which is pivotally mounted one end of a clutch lever 55 by means of which clutch members 35 are operated. Extending upwardly from shaft 52, intermediate the ends thereof, is a lever 56 to the 35 upper end of which is pivotally connected one end of a connecting bar 58. The other end of bar 58 is pivotally connected to a link 58^a loosely mounted upon the forward shaft 52. Link 58^a is connected by a link 40 45 59 to an operating lever 69 pivotally mounted at its lower end in frame 10. The forward shaft 52 is connected by a link 70^a in a similar or any other suitable manner to an operating lever 70 pivotally mounted at the 50 side of lever 69. It will be noted that when the operating mechanism just described is in its neutral position the brake band will be in its operative position and that as the operating handles are moved to bring either 55 end of the clutch into engagement with the respective pinion gear, the brake will be released.

Rigidly mounted upon shafts 21 and 22, near the inner sides of members 17 and 18, 60 are spur gears 71 and 72 which are in operative engagement with the teeth 73 of the bowl elevating members 74. Loosely mounted upon shafts 21 and 22, at each side of gears 71 and 72, are plates 75 and 76 65 which plates straddle bars 74 and have rev-

olubly mounted in their free ends rollers 77 which bear against the outer faces of bars 74 to hold the same in operative engagement with the spur gears 71 and 72.

Pivotedly mounted upon the lower ends 70 of bars 74 are the scraper bowls 78 and 79. Extending from the outer sides of bowls 78 and 79 to the inner sides of frame 10 are links 80 and 81. Pivotally connected to the outer sides of bowls 78 and 79, at the rear 75 of the upper edges thereof, are the retaining members 82. As shown in Fig. 3, members 82 extend upwardly and forwardly at an angle and have their free ends widened and in these widened ends are provided 80 elongated openings 83 at the upper ends of which are recesses 84 in which are adapted to rest the locking pins or studs 85. Extending inwardly from the inner faces of members 82 and projecting across the upper 85 edges of the sides of the bowls are studs 86 which studs are engaged by the top of said edges as the bowl is moved upwardly, thereby swinging the free ends of members 82 upwardly and releasing the same from the locking stud 85 and permitting the bowls to tip forwardly. Pivotally mounted at one end upon the inner faces of the sides of the bowls, near the top edges thereof, are arms 87 which curve forwardly and downwardly 90 and have mounted on their forward ends the gate 88 which normally acts to close the front open end of the bowls. Extending outwardly from the outer face of frame 10 is a stud 89 over which pass the arms 87 and which serves to open or elevate the gate as the bowls are moved downward to their loading position and also as the bowl is tipped to its dumping position.

In the operation of our device the parts 105 will normally lie in the positions shown in Figs. 1, 2 and 3 of the drawings. As the device is propelled along the ground when it is desired to operate the scraper bowls the operating handle will be moved forwardly, thereby causing the forward ends of the clutch members to engage the clutch portions of the forward bevel pinions and at the same time releasing the brake which 110 will permit the bowls to be lowered the desired distance, at which time the operating handle will be returned to its normal vertical position. When the bowls are loaded to the desired amount the operating handle will be moved rearwardly, thereby 115 bringing the rearmost end of the clutch members into engagement with the rearmost bevel pinions, whereby the bowls are elevated a sufficient distance above the ground to clear the same, when the operating handle is again returned to normal, at the same time setting the brakes to hold the bowls in their elevated positions. When it is desired to dump the bowls the operating handle will again be moved rearwardly and 120 125 130

the bowls elevated until the top of the bowls engage studs 86 and elevate members 82, thereby releasing recesses 84 from the locking studs 85, which permits the front ends 5 of the bowls to tip downwardly, at the same time arms 87, engaging stud 89, will be held in their elevated position, thereby permitting the front ends of the bowls to fall away from gate 88 permitting the contents 10 to pass out. When it is desired to spread the dirt as it passes from the bowls the bowls will be elevated just sufficiently to be tipped the desired amount, the gate being open a corresponding distance. By reversing 15 the operating handle the bowls will be lowered a sufficient distance until stud 85 again engages recess 84 and the bowl will be brought to an even keel.

Having described our invention what we 20 claim is:

1. In a scraper the combination of a wheeled frame; a pair of spaced transverse shafts journalled thereon; a bevel gear mounted on one end of each of said shafts; 25 a longitudinal shaft journalled in said frame; a pair of bevel gears loosely mounted on said shaft for each of said first mentioned gears, in mesh therewith; a clutch member slidably but non-revolubly mounted 30 on said shaft between each pair of said bevel gears; means to move either one of said clutches to engage either one of each pair of bevel gears; spur gears rigidly mounted upon said transverse shaft, one at 35 each end thereof; a scraper bowl for each of said shafts; a rack pivotally mounted at its lower end on each side of said bowls to extend upwardly and having teeth adapted to operatively engage said spur gears, 40 whereby when said transverse shafts are rotated said bowls will be adjusted vertically; an operating shaft mounted transversely in said frame intermediate said first mentioned transverse shafts; an operative connection between said last transverse 45 shaft and said longitudinal shaft; an operative connection between said last transverse shaft and the axle of said frame; a brake drum on the ends of said first transverse 50 shafts; braking means mounted on said frame adapted for operative engagement with said brake drums; and means carried by said frame for operating said clutches and releasing said braking means synchronously.

2. In a wheeled dirt scraper a frame; a pair of transverse shafts rotatably mounted on said frame; a driving shaft revolvably mounted in said frame transversely thereof; 60 a driven shaft revolvably mounted in said frame to extend longitudinally of one side thereof; an operative connection between said driving and driven shafts; operative connections between said driven and transverse shafts adapted to rotate said trans-

verse shafts in either direction; manually operated means to select the direction of rotation of said transverse shafts mounted on said driven shaft; a scraper bowl for each of said transverse shafts; a spur gear 70 rigidly mounted on each end of said transverse shafts; a rack carried by said scraper bowls in engagement with said spur gears, whereby when said transverse shafts are rotated said bowls will be elevated or lowered; braking means between said transverse shafts and said frame adapted, upon the release of the rotating means, to hold 75 said transverse shafts against rotation, and upon the operation of said selecting means, 80 to release said shafts; and means between said frame and bowls adapted, upon the elevation of said bowls to a predetermined height, to dump the same.

3. In a wheeled dirt scraper a vehicle 85 frame; a plurality of transverse shafts rotatably mounted on said frame; a longitudinal shaft revolvably mounted on said frame in alignment with one of the ends of said transverse shafts; operative connections between said longitudinal and transverse shafts capable of connection and disconnection; a driven shaft mounted transversely on said frame; an operative connection between said driven shaft and said longitudinal shaft; means adapted to be operated by the movement of said vehicle frame to rotate said driven shaft; a plurality of scoops carried by said frame; spur gears mounted at each end of said transverse shafts; a toothed 90 bar pivotally connected to each side of each of said scoops having their free ends in operative engagement with the spur gears of their respective shaft, whereby the rotation of said shafts will elevate said scoops; means between said frame and transverse shafts adapted to hold said shafts against rotation; means between said scoops and said frame adapted, when said scoops are elevated, to dump the same; and manually operated means to connect and disconnect the operative engagement between said longitudinal and transverse shafts.

4. A wheeled dirt scraper comprising a vehicle frame; a scraper bowl; supporting means for said bowl carried by said frame in which the same is rockably mounted and being capable of movement vertically; a transverse shaft revolvably mounted on said frame; gear wheels mounted one at each end of said shaft to rotate therewith adapted for operative connection to said scraper bowl supporting means; a connection from said transverse shaft to the axle of said vehicle wheels, whereby said wheels and shaft rotate in unison; means to render said last means inoperative; means operated by the upward movement of said bowl to dump the same; a closure for the open end of said bowl; means operated by the dumping of 100

said bowl to open said closure; means carried by said frame adapted to hold said bowl in its adjusted elevated position; and manually operated means to release said holding means at the will of the operator.

5. In a wheeled dirt scraper a vehicle frame; a pair of transverse shafts rotatably mounted on said frame; a driving shaft revolubly mounted in said frame transversely thereof; an operative connection between said driving shaft and one of the wheels of said vehicle frame, whereby said wheel and shaft rotate synchronously; a driven shaft revolubly mounted in said frame at one side 15 thereof to extend longitudinally in alignment with the ends of said transverse shafts; an operative connection between said driving and driven shafts; operative connections between said driven and transverse shafts adapted to be operated to cause 20 said transverse shafts to rotate in either direction; means to manually operate said operative connections to render the same oper-

ative or inoperative; a scraper bowl for each of said transverse shafts; gear wheels rigidly mounted, one at each end, on said transverse shafts; an elevating bar mounted at each side of each of said bowls having their upper ends in operative engagement with said gear wheels, whereby when said shafts are rotated said bowls will be moved vertically; means between said frame and bowls adapted to dump the same at a predetermined time; a closure for the front end of said bowls mounted in said frame; and means carried by said frame adapted upon the elevation of said bowls to cause said closure to obstruct the open end thereof; and means carried by said frame adapted upon the dumping of said bowls to remove 40 said closure from its obstructive position.

In witness that we claim the foregoing we have hereunto set our hands this 27th day of November, 1922.

CHARLES E. BALL.
SAMUEL H. BALL.
